FIG. 2

UNITED STATES PATENT OFFICE.

JACOB ARBESS AND SAMUEL BRISKER, OF MONTREAL, QUEBEC, CANADA.

COMBINATION STEP-LADDER AND IRONING-BOARD.

1,229,698.

Specification of Letters Patent. Patented June 12, 1917.

Application filed January 2, 1917. Serial No. 140,119.

To all whom it may concern:

Be it known that we, JACOB ARBESS and SAMUEL BRISKER, both subjects of the King of Great Britain, residing at Montreal, 5 Province of Quebec, Canada, have invented certain new and useful Improvements in Combination Step-Ladders and Ironing-Boards; and we do hereby declare that the following is a full, clear, and exact description of the invention, such as will enable others skilled in the art to which it appertains to make and use the same.

The present invention relates to a convertible article of furniture and more particularly to a combination step ladder and ironing board.

An object of the present invention is to provide a detachable ironing board which may be connected to an ordinary step ladder whereby the former may be easily and readily presented to use, but when not in use it can be folded upon the step ladder so as to take no additional space and only slightly increase the weight thereof or the ironing board may be readily removed from the step ladder.

A further object of the present invention is to provide a strong, durable and efficient device of the character aforesaid which is very simple in construction, comparatively inexpensive in the cost of manufacture, thereby rendering the same commercially desirable.

With the above and other objects in view which will hereinafter appear as the description continues, the invention consists of the novel features of construction, combination and formation of parts as will be hereinafter more fully described and particularly pointed out in the appended claims.

In the accompanying drawings has been shown the simple and preferred form of the invention, it being, however, understood that no limitation is necessarily made to the precise structural details herein exhibited, but the right is hereby reserved to any changes, alterations or modifications to which recourse may be had that come within the scope of the claims without departing from the spirit of the invention or sacrificing the efficiency of the same.

In the accompanying drawings:

Figure 1 is a perspective view of the step

ladder and ironing board embodying the present invention; and,

Fig. 2 is a vertical sectional view taken through the same when folded.

We refer now more particularly to the accompanying drawings wherein like and corresponding parts are designated by similar reference characters throughout the several views.

The step ladder herein shown comprises the side rails 1 which are connected by means of the usual rungs or steps 2 and a top step 3 is arranged at the top of the side rails. Connected to the top step 3 and the side rails 1 are the usual side bearing plates

4. The prop for supporting the step ladder comprises two side rails 7 which are reinforced by the transverse bars 8 and the diagonal bars 9. These bars 8 and 9 are secured to the inner face of the rails 7. Connecting the side plates 4 is the usual round

or rod 10 to which is pivotally connected the side rails of the prop and the prop is connected and braced to the side rails of the rod by means of the usual foldable and locking brace 11. In the foregoing an ordinary household foldable step ladder is shown and described and the purpose of the present invention is to provide an ironing board which may be readily connected thereto or carried therewith.

This ironing board comprises a board 12 which may be of the usual configuration of an ordinary ironing board having its inner end pivotally and detachably connected to the rod 10 and its opposite end is supported by means of a pair of legs 13 which are connected to the lower face of the ironing board by means of the hinges 14. The supporting legs 13 are braced by means of the cross bars

15 and are connected to the ironing board by means of the foldable braces 16 which are the same as the braces 11. When presenting the ironing board for use it may be set up as better illustrated in Fig. 1, but in folding the ironing board upon the step ladder the legs 13 may be swung upon their hinged connections and rest against the lower face of the ironing board 12. The ironing board is then released and will rest between

the rails 7 upon the bars 8 and 9 and the weight of the board 12 will hold the legs 13 within the prop section of the ladder where-

by the ironing board may be readily folded

upon the step ladder without taking up any additional room and only adding a slight amount of weight thereto. When it is desired, the pivotally mounted lugs or latches 5 17 may be connected to the rails 7 so as to lock the ironing board in place within the prop section of the step ladder, thereby permitting the step ladder to be folded and preventing the ironing board from being 10 swung out of folded position. The detachable and pivoted connection between the board 12 and the prop section of the step ladder comprises a pair of spaced hooks 16 which are connected to the rod 10 and it is 15 obvious that when it is so desired the board 12 may be readily detached from the step ladder and permitted to be connected to any other articles of furniture.

Having thus fully described our invention, what we claim as new and desire to secure by Letters Patent is:

1. A combination step ladder and ironing board comprising a step ladder consisting of a step portion and a prop portion, a 25 rod extending transversely of said prop portion for pivotally connecting the ladder to the step portion, an ironing board pivotally

connected to said rod supporting legs carried by one end of said ironing board and said ironing board and supporting legs 30 adapted to rest within said prop portion when in their folded position for the purpose specified.

2. A convertible article of furniture of the character described comprising a step 35 ladder consisting of a step portion, a rod carried by said step portion and extending transversely thereof, a prop portion pivotally connected to said rod, an ironing board, a pair of hooks carried by said ironing board and adapted to be detachably and pivotally connected to said rod, supporting legs hingedly connected to the outer end of said ironing board, said supporting legs and ironing board adapted to rest within said 40 prop portion when in their folded position and latch members carried by said prop portion for locking said ironing board within 45 said prop portion for the purpose specified.

In witness whereof we have hereunto set 50 our hands.

JACOB ARBESS.
SAMUEL BRISKER.
